UNITED STATES PATENT OFFICE.

JAMES STANLEY AND WALTER H. CARSON, OF WEST POINT, GEORGIA.

CALENDER RACK.

Application filed June 3, 1921. Serial No. 474,838.

To all whom it may concern:

Be it known that we, JAMES STANLEY and WALTER H. CARSON, citizens of the United States, and residents of West Point, in the 5 county of Troup and the State of Georgia, have invented certain new and useful Improvements in Calender Racks, of which the following is a specification.

This invention relates to calender-racks 10 especially adapted for use on picking machines employed in textile mills.

Briefly stated, an important object of this invention is to provide automatic means whereby the calender-rack is rendered inoperative when the load or strain on the 15 same exceeds a predetermined point.

As set forth in the United States Letters Patent to John H. Tice, No. 1,361,508, the several parts of the calender-rack frequently 20 break due to excess strain and production is greatly retarded during the period of repair. It is therefore, an important aim of this invention to provide a calender rack body having a rack or toothed section secured in 25 position by a pair of frangible pins which will be sheared off when the load on the calender rack exceeds the strength of the several pins. By having the toothed section of the rack secured in position by means of 30 the frangible and detachable pins the toothed section may be readily renewed should one or more of the teeth become mutilated. Further the frangible pins extending through the shank of the rack and the tongue of the 35 toothed section are highly accessible so that the same may be replaced with a minimum consumption of time and a minimum of effort on the part of the attendant.

Other objects and advantages of the invention 40 will be apparent during the course of the following description.

In the accompanying drawing forming a part of this application and in which like numerals are employed to designate like 45 parts throughout the same,

Figure 1 is a perspective of the improved calender rack.

Figure 2 is a side elevation of the same, the shank of the rack being shown in section 50 to illustrate the frangible connection between the toothed section and the shank of the rack.

Figure 3 is a transverse sectional view taken on line 3—3 of Figure 2.

55 In the drawing wherein for the purpose of illustration is shown a preferred embodiment of the invention the numeral 5 generally designates the improved rack which consists of an elongated shank 6 having a laterally projecting V-shaped integral head 7 to 60 which a detachable head 8 is connected by means of side plates 9. The side plates 9 which are arranged in spaced parallel relation are disposed on opposite sides of the integral head 7 and are securely connected 65 to the same by means of fastening devices 10 possessed of sufficient strength to at all times provide a driving connection between the removable and integral heads.

The side plates 9 form a bearing means 70 for anti-friction elements 13 and 14 which are rotatably supported in bushings carried by the side plates. As is well known the anti-friction rollers cooperate with the lap pin of the picking machine in the formation 75 of the laps and in order that the rollers 13 and 14 may be readily renewed the side plates may be detached. However, the head of the rack is not possessed of the safety features as outlined in the aforesaid patent 80 as the side plates 9 are securely connected to the integral head 7 by means of the pins 10 which are possessed of ample strength to at all times provide a driving connection 85 between the detachable and integral heads.

Specifically this improvement resides in providing a rack section or toothed section 20 having its under side formed with a longitudinal tongue 21 snugly received in a longitudinal groove 22 formed in the opposed sides of the rack shank 6. In order 90 that the tongue 21 may be held within the groove 22 a pair of frangible pins 24 are passed through the end portions of the tongue and the adjacent portions of the shank. When the train of gears associated 95 with the toothed section 20 transmits an excessive load to the calender rack the frangible pins 24 are severed so as to break the driving connection between the section 20 and the rack. In order that the toothed section 20 may be prevented from moving into the vicinity of the head of the rack we have reduced the shank for the length of the toothed section to provide a shoulder 26 100 which contacts with the adjacent end of the toothed section 20 and limits the upward movement of the same. Also the upper end of the tongue 21 contacts with the upper end wall of the groove 22 so as to limit the 105 upward movement of the toothed section.

By securing the toothed section 20 to the

shank of the rack by the frangible pins 24 no excessive load is transmitted to the head of the rack, which load would be likely to break the parts of the machine associated 5 with the rollers 13 and 14. Further should any of the teeth in the rack section 20 become mutilated the rack section may be readily renewed without the necessity of renewing the entire shank. This operation 10 may be quickly performed since the section 20 is held in position solely by means of the pins 24.

As illustrated in Figure 3, case hardened steel bushings in the tongue 21 and in the 15 adjacent portions of the shank receive the pins 24 so that the pin will not be permitted to bend when the strain is excessive. The presence of the case hardened bushings which are designated by the numeral 30 20 prevents the openings in the rack from being enlarged as a result of continued breaking of the pins.

It will be seen that the tongue and groove connection between the rack and the shank 25 provides a means to guide the movement of the shank upward after the pins have been sheared off. Of course the rack remains stationary after the pins have been sheared off and the shank and head that 30 holds the lap roll and the pin are free to travel upwardly with the movement of the machine.

Having thus fully described the invention what we claim as new and desire to secure by Letters Patent is:—

1. In a picking machine, the combination with a shank having a head rigidly and securely connected thereto and provided with lap pin cooperating means, of a renewable 40 rack associated with said shank, and frangible means connecting the renewable rack to said shank whereby the driving connection between the renewable rack and the shank is broken when the strain exceeds 45 a predetermined point.

2. A calender rack for cotton picking machines comprising a shank having a reduced portion defining a shoulder, a toothed section applied to said reduced portion, frangible means connecting said toothed section to said shank, and a head connected to said shank, said shoulder constituting a means to limit the endwise movement of the toothed section when said frangible means are severed.

3. A calender rack for cotton picking machines comprising a shank having a reduced portion defining a shoulder, a toothed rack section applied to the reduced portion of

said shank and contacting with said shoulder, and frangible pins connecting said toothed section to said shank.

4. A calender rack for cotton picking machines comprising a shank having a groove, a toothed section having a tongue received in said groove, and frangible means extending through said tongue and said shank.

5. In a picking machine, the combination with a shank having a head rigidly and securely connected thereto, said head being 70 provided with lap pin cooperating means of a renewable rack associated with said shank, and frangible means connecting the renewable rack to said shank whereby the driving connection between the renewable 75 rack and the shank is broken when the strain exceeds a predetermined point, there being means between the renewable rack and the shank to guide the shank with relation to the rack when the driving connection 80 is broken.

6. A rack comprising a shank provided with a shoulder and a groove terminating at the shoulder, a toothed section having a tongue received in said groove, said shank 85 and said tongue being provided with aligned openings, and frangible pins extending through said openings and detachably connecting the toothed section to said body, said toothed section having contact 90 with said shoulder.

7. A rack comprising a shank, a rack associated with said shank and frangible means connecting the rack to the shank, there being a shoulder arranged in the path 95 of travel of said rack to limit the endwise movement of the rack when the frangible means are severed.

8. A rack for picking machines comprising a shank, a toothed section associated 100 with said shank, there being a tongue and groove connection between the shank and the toothed section, and frangible means extending through said tongue and connecting the toothed section to the shank.

9. A rack for picking machines comprising a shank, a toothed section associated with said shank, there being a tongue and groove connection between the shank and the toothed section, and frangible means extending through said tongue and connecting the toothed section to the shank, said shank being provided with a shoulder constituting a means to limit the endwise movement 110 of the toothed section when the frangible means are severed.

JAMES STANLEY.
